ABSTRACT OF THE DISCLOSURE

Arrangement and method for constructing multispan bridges across water in successive spans from heavy prefabricated elements in which a pair of laterally outward longitudinally displaceable auxiliary girders, cantilevered on already provided longitudinally spaced apart piers at the height at which the bridge is being built, serve as tracks for independently traveling bridge crane means situated thereon, and an independently removable island platform positioned in the water ahead of the free ends of the auxiliary girders serves as support for such free ends when island crane means thereon draw such free ends and in turn the auxiliary girders forward for such support and as working platform, to permit use of said bridge cranes to transport prefabricated elements forward to said free ends and manipulation in conjunction with said island crane of such elements to assemble and construct the next bridge span below and laterally between said auxiliary girders, as the case may be, independently of weather, water and terrain conditions.

The present invention relates to an arrangement and method for constructing multispan bridges or the like across water, whose superstructures are successively constructed with the aid of auxiliary girders which are supported on already constructed bridge piers and which are movable in the longitudinal direction of the bridge, the fore-ends of the auxiliary girders forming cantilevers which are held by an auxiliary support.

In a known successive span bridge construction arrangement and method, a travelling girder, which serves to advance structure girders which carry the formwork and the weight of the superstructure during concreting, is simultaneously used in order to construct, while working from it, the bridge piers together with their foundations. The equipment necessary for this is mounted on the cantilever arm of the travelling girder which may also be supported by an auxiliary support.

This known arrangement and procedure has the basic disadvantage that only relatively small lifting equipment can be used thereon since the size of the travelling girder, even if it is supported at its free end, has limits which are determined by economic considerations. Since the bringing in of material required for constructing the subsequent piers causes difficulties as long as the part of the superstructure lying above the structure girders has not been finished and hardened, the constructional material has to be brought along via the bottom of the valley or by means of boats on the water below, in which case one is dependent on the terrain or water conditions. Furthermore it is practically impossible to manufacture the piers and their foundations from large prefabricated concrete sections since this requires very heavy lifting equipment which both because of its great weight and because of its large size cannot be mounted at the front end of a cantilever arm of the travelling girder.

It is the object of the present invention to avoid the foregoing disadvantages and to provide an arrangement

2

and method for constructing multispan bridges and the like, passing over water, according to which superstructures and understructures of the bridge can be constructed from the head of the bridge without reference to the weather conditions, terrain conditions and water conditions.

Other and further objects of the present invention will become apparent from a study of the within specification and accompanying drawing, in which:

FIG. 1 shows a schematic longitudinal view of a landing bridge, constructed according to one embodiment of the present invention, in the course of construction;

FIG. 2 shows a schematic cross-sectional view through the bridge taken along the line II—II of FIG. 1;

FIG. 3 shows a schematic cross-sectional view through the bridge taken along the line III—III of FIG. 1;

FIG. 4 shows a schematic view corresponding to FIG. 3, at a different stage of construction; and

FIG. 5 shows a schematic view similar to that of FIG. 2 which illustrates the construction of a superstructure for the bridge.

It has been found in accordance with the present invention that the required task is solved by auxiliary girders which serve both to construct the superstructures and also as a track way for transportation means for the constructional material to be used for the superstructures and understructures, with such auxiliary girders resting, at their ends which face away from the constructional work, on the platform of a lifting island from which the understructures can be constructed.

There is provided an arrangement for constructing multispan bridges across water in successive spans mainly from heavy prefabricated elements, which comprises at least two longitudinally spaced apart transverse cross-beams supported at the height at which the bridge is to be built, a pair of transversely spaced apart longitudinal auxiliary girders laterally outwardly resting on said cross-beams and spanning the longitudinal distance therebetween, said auxiliary girders being longitudinally displaceable with respect to said crossbeams and having a length greater than the longitudinal distance between said crossbeams to provide corresponding cantilever free ends of said auxiliary girders longitudinally extending substantially beyond said crossbeams, an island platform independently removably positioned in the water ahead of the corresponding free ends of said auxiliary girders at a distance corresponding to the next span to be constructed in the forward longitudinal direction of construction of the bridge, island crane means and support means disposed on said island platform, and independently traveling bridge crane means disposed for longitudinal travel on said auxiliary girders, whereby said free ends of the auxiliary girders may be drawn by said island crane means longitudinally forward to said island support means for resting support thereon and in turn the remainder of said auxiliary girders advanced along said crossbeams, said bridge crane means may transport heavy prefabricated pile, pier, crossbeam, main bridge span girder and superstructure elements longitudinally along said auxiliary girders supported by said island support means for assembly below and for assembly laterally between said auxiliary girders, as the case may be, within the range of conjunctive operation of said island crane means and said bridge crane means to provide the next span unit of the bridge, and upon displacing longitudinally said removably positioned island platform in the forward direction of construction of the bridge a distance corresponding to the next span, the drawing forward of said auxiliary girders and the bridge assembly procedure may be repeated independently of weather, water and terrain conditions.

More particularly, the crossbeams are provided with

lateral brackets at their ends which have roller mountings thereon in operative contact with said auxiliary girders to accommodate the longitudinal displacement of said auxiliary girders with respect to said crossbeams while supporting said auxiliary girders thereon at a level corresponding substantially to that of the main bridge span girders yet laterally outwardly thereof.

Preferably the island support means is in the form of a pair of laterally spaced apart transversely displaceable island brackets having hydraulic jack means thereon for transversely alignable corresponding operative supporting contact with said free ends of the auxiliary girders.

In the same way a method is provided for constructing multispan bridges across water in successive spans mainly from heavy prefabricated elements, which comprises establishing at least two longitudinally spaced apart transverse crossbeams supported at the height at which the bridge is to be built as well as a pair of transversely spaced apart longitudinal auxiliary girders laterally outwardly resting thereon and spanning the longitudinal distance therebetween, such that said auxiliary girders are longitudinally displaceable with respect to said crossbeams and have a length greater than the longitudinal distance between said crossbeams to provide corresponding cantilever free ends of said auxiliary girders longitudinally extending substantially beyond said crossbeams, providing independently travelling bridge crane means disposed for longitudinal travel on said auxiliary girders, maintaining an island platform independently removably positioned in the water ahead of the corresponding free ends of said auxiliary girders at a distance corresponding to the next span to be constructed in the forward longitudinal direction of construction of the bridge with island crane means and island support means disposed thereon, drawing said free ends of the auxiliary girders by said island crane means longitudinally forward to said island support means and placing said free ends in resting support thereon while advancing in turn the remainder of said auxiliary girders along said crossbeams, transporting by said travelling bridge crane means corresponding heavy prefabricated pile, pier, crossbeam, main bridge span girders and superstructure elements longitudinally along said auxiliary girders while supported by said island support means, sinking said pile and pier elements at the appropriate bridge span distance to form supports for a corresponding crossbeam element and mounting a crossbeam element on said pile and pier elements with the aid of said island crane means, laying corresponding main bridge span girder and superstructure elements laterally between said auxiliary girders and at substantially the same level thereof with the aid of said travelling bridge crane means, and repeating said drawing, placing, transporting, sinking, mounting and laying steps at least one more time, whereby to construct a multispan bridge across water in successive spans.

Such an arrangement and method have the advantage that the construction of the bridge is entirely independent of water, terrain and weather conditions. The entire material used for constructing the bridge can be brought along from the land side, via the bridge sections which have already been finished and thence the auxiliary girders. This has especially proved advantageous when constructing bridges which lead out into the open sea like landing piers, where the supply of materials by boat is impossible in choppy or heavy seas. Moreover the use of a lifting island, a constructional apparatus itself well known, has the advantage that not only are the auxiliary girders adequately supported at any desired height at their free projecting ends, but also the entire device for constructing the understructures can be placed on the lifting island platform without difficulties, thus relieving the auxiliary girders and their undersupports of such heavy equipment. The lifting island is able to carry very heavy lifting equipment so that the understructure can also be constructed out of large prefabricated concrete sections.

When the platform is raised up on the lifting island, the latter will also be able to withstand heavy storms and can even be moved on effortlessly and rapidly to a safe location.

When constructing a new pier in accordance with one embodiment of the procedure of the present invention the lifting island is first brought into position in front of the end of the particular pier which is to be erected. The auxiliary girders are then advanced into the bridge span which is limited, on the front-structure side, by the piers which are to be erected, and are grasped at their freely projecting fore-ends by lifting equipment arranged on the lifting island and then further advanced whilst supported in this manner and set down on the edge of the lifting island platform. This method of working has the advantage that the auxiliary girders do not have to extend over two bridge spans. Their length only has to be about 1.5 times that of the bearing distance between supports since they can, at their freely projecting ends be supported by the lifting equipment stationed on the lifting island during the last phase of advance. Depending on the radius of the lifting equipment, i.e., crane booms, this support can already become effective at one half or one third of the travel.

It will be realized that according to the instant invention both the superstructures and the understructures of the bridge are preferably manufactured from prefabricated units, such as reinforced or prestressed concrete, which may also be of a relatively large size, and which thus ensure rapid progress of the building work.

In accordance with a particular feature of the present invention, a device for carrying out the successive span construction includes two auxiliary girders, carried movably and fixably appropriately on the bridge piers, along both sides of the superstructure which is to be erected, and at least one Portal crane travelling on such auxiliary girders, this crane taking prefabricated building sections and/or building materials brought along via the superstructures which have already been finished and passing them on to the point where they are to be incorporated into the next successive span to be erected.

The arrangement of the auxiliary girders alongside the superstructures which are to be erected has the advantage that the auxiliary girders can lie at the same height or level as the main bridge span girders of the superstructure. Their support is therefore particularly simple especially when the piers are formed by several pillars which are connected to one another by means of a crossbeam at the top of the pillars. By arranging the auxiliary girders laterally to the superstructure both the movement of main girders, consisting of prefabricated sections made of reinforced or prestressed concrete, and the transportation of prefabricated sections, such as piles and pillars for the understructure or piers is rendered particularly simple, and the transportation of the understructure parts does not interfere with the assembly and casting of the superstructure parts.

Referring to the drawings, and especially FIG. 1, 10 denotes a landing bridge built out to sea, for ships riding at the roads, this bridge being subdivided in a longitudinal direction into a number of bridge spans 11, 12, 13 and 14. However, only a part of the bridge is shown in FIG. 1. The bridge is built out from the land in the direction of arrow 15.

The spans 11, 12, 13 and 14 of the superstructure are bounded by bridge piers 16, 17, 18 and 19, the last just going into place, which in the present example of an embodiment are each formed by two single pillars 16a and 16b, 17a and 17b, 18a and 18b and 19a and 19b, as the case may be, spaced apart from one another in a transverse direction, and connected to one another at their tops ends by corresponding crossbeams 16c, 17c, 18c and 19c.

The main bridge span girders 20 of the superstructure bridging the gaps at spans 11, 12, 13 and 14 rest on the

crossbeams 16c, 17c, 18c and 19c. They, as well as the building supports or piers 16, 17, 18 and 19 and their crossbeams 16c, 17c, 18c and 19c, consist preferably of prefabricated parts made of prestressed concrete. The main girders 20 are connected to one another by a track plate 40 (see FIG. 5) lying on top which need not be represented in more detail here.

Steel lateral brackets 35 are mounted on both end faces of each crossbeam 16c, 17c, 18c and 19c, and on these, i.e., at both sides of the superstructures or main girders 20, a corresponding steel auxiliary girder 21 having a box beam section is carried on roller mountings 22 so as to be movable in a longitudinal direction and fixable, i.e., at their free or cantilever ends 23. The auxiliary girders 21 in the present embodiment as shown span two bridge spans 13 and 14 and at their rear end project somewhat into span 12. At their front freely projecting or cantilever end 23 they rest, with interposition of hydraulic jacks 24, on island brackets 25. Brackets 25 are mounted at the edge of the platform 26 of an independently removably positioned lifting island 27 so as to be sideways adjustable (see FIG. 3), the island being supported on the bed 39 of the water by means of its supporting legs 28.

Two portal cranes 29 and 30 run on the auxiliary girders 21 which act as tracks therefor. The cranes take the prefabricated sections needed for constructing the understructures and superstructures from the rolling trucks 31 and 32 which run on the main girders 20 of the bridge (see FIG. 2), and transport them in the longitudinal direction and also in the transverse direction of the bridge (see FIGS. 4 and 5). The parts needed for the understructures are taken over by a derrick crane 33, which is anchored to the platform 26 of the lifting island. On heaving in and incorporating the prefabricated sections required for the understructure the derrick crane 33 is assisted by two small jib cranes 34, of which only one is represented in the drawing, which can be swivelled about the supporting legs 28 of the lifting island which face the bridge and which stand on the platform 26 of the lifting island.

The bridge is constructed in the following manner:

It is assumed that the bridge piers 16, 17 and 18 have already been constructed and that at least the main girders 20 of the superstructure bridging the gaps 11 and 12 have been laid and assembled. The auxiliary girders 21 rest on the brackets 35 of the crossbeams 16c, 17c and 18c in such a way that the front ends 23 of the auxiliary girders 21 are supported by appropriate brackets 35 of the crossbeam 18c.

In order to be able to start the construction of the bridge pier 19 the lifting island 27 is brought into position 50 in front of the bridge pier 19 which is to be constructed. The auxiliary girders 21 are then advanced into the bridge span 14 with their freely projecting fore-ends 23 being supported by the load hooks of the derrick crane 33 as soon as they have approximately reached the middle of the superstructure span 14. The auxiliary girders are then 55 further advanced, with simultaneous lifting of the jib 37 of the derrick crane 33, and are placed with their freely projecting fore-ends 23 on the brackets 25 of the lifting island 26. Since these brackets 25 can be moved sideways, they can be brought precisely flush with the auxiliary girders 21 if the lifting island is in a position which is somewhat sideways displaced relative to the longitudinal axis of the bridge.

In the represented embodiment not only the bridge 65 piers but also their base foundations are constructed from prefabricated sections. For this purpose bores are made in the sea bed 39 by means of conventional boring equipment which need not be represented in any detail and which is placed together with the derrick 33 on the platform 26 of the lifting island 27. Then prefabricated piles 38 made of reinforced concrete are introduced into these bores. These piles 38 are successively brought along from the land, from the beginning of the bridge, in the direction of the arrow 15, on rolling trucks 31 and 32 travelling 70 75

over the main girders 20 of the superstructures which have already been finished, until they come to span 12. There they are taken over by the portal cranes 29 and 30 as shown on the left-hand side of FIG. 1.

5 The portal cranes 29 and 30 then travel on the auxiliary girders 21 into span 14. The front end of the pile 38 is then taken by the jib cranes 34 and slowly lowered whilst the derrick crane 33 takes the rear end of the pile and lifts it so that the pile can be introduced into the bore hole in the seat bed 39 as soon as the pile hangs approximately vertically (right-hand half of FIG. 1). The piles 38 can then be rammed even more deeply into the bed by means of a conventional rammer suspended from the derrick 33 but not shown in any detail here.

10 After introducing the piles the upper parts of pier 19 of the building supports, which also consist of prefabricated sections, are brought along from the land in the same manner, via the bridge 10, and are assembled. Thereafter the prefabricated crossbeam 19c is brought along, lifted by the derrick 33, turned, placed on the tops of the supports 19a and 19b and coupled with them (see FIG. 4).

15 During the assembling of the understructures 38, 19a, 19b and 19c, the main girders 20 for the bridge span 13 can be separately brought along and put in place. This can also be done by means of the portal cranes 29 and 30, which not only permit longitudinal transportation but also transportation of the main girders 20 in a transverse direction and thus permits precise laying of the individual parts (see FIG. 5).

20 Naturally, where various constructional parts have been defined in terms of "means" in the instant specification and/or claims, such means have been illustrated in the accompanying drawings as specific elements, but in accordance with the present invention, such means contemplate any and all elements usable to achieve the combination arrangement of the invention, as the artisan will appreciate, so long as the disposition of the parts in question is maintained, and any and all such constructional elements are contemplated herein just as if prolix enumeration thereof were set forth in detail herein.

25 It will be appreciated that the instant specification and drawings are set forth by way of illustration and not limitation, and that various modifications and changes may be made without departing from the spirit and scope of the present invention which is to be limited only by the scope of the appended claims.

30 What is claimed is:

1. Arrangement for constructing multispan bridges across water in successive spans mainly from heavy prefabricated elements, which comprises at least two longitudinally spaced apart transverse crossbeams supported at the height at which the bridge is to be built, a pair of transversely spaced apart longitudinal auxiliary girders laterally outwardly resting on said crossbeams and spanning the longitudinal distance therebetween, said auxiliary girders being longitudinally displaceable with respect to said crossbeams and having a length greater than the longitudinal distance between said crossbeams to provide corresponding cantilever free ends of said auxiliary girders longitudinally extending substantially beyond said crossbeams, an island platform independently removably positioned in the water ahead of the corresponding free ends of said auxiliary girders at a distance corresponding to the next span to be constructed in the forward longitudinal direction of construction of the bridge, island crane means and island support means disposed on said island platform, and independently traveling bridge crane means disposed for longitudinal travel on said auxiliary girders, whereby said free ends of the auxiliary girders may be drawn by said island crane means longitudinally forward to said island support means for resting support thereon and in turn the remainder of said auxiliary girders advanced along said crossbeams, said bridge crane means may transport heavy prefabricated pile, pier, crossbeam, main bridge span girder and superstructure elements longi-

tudinally along said auxiliary girders supported by said island support means for assembly below and for assembly laterally between said auxiliary girders, as the case may be, within the range of conjunctive operation of said island crane means and said bridge crane means to provide the next span unit of the bridge, and upon displacing longitudinally said removably positioned island platform in the forward direction of construction of the bridge a distance corresponding to the next span, the drawing forward of said auxiliary girders and the bridge assembly procedure may be repeated independently of weather-water and terrain conditions.

Arrangement according to claim 1 wherein said crossbeams are provided with lateral brackets at their ends which have roller mountings thereon in operative contact with said auxiliary girders to accommodate the longitudinal displacement of said auxiliary girders with respect to said crossbeams while supporting said auxiliary girders thereon at a level corresponding substantially to that of the main bridge span girders yet laterally outwardly thereof.

3. Arrangement according to claim 2 wherein said island support means is in the form of a pair of laterally spaced apart transversely displaceable island brackets having hydraulic jack means thereon for transversely alignable corresponding operative supporting contact with said free ends of the auxiliary girders.

4. Arrangement according to claim 3 wherein said island crane means includes a main derrick crane and a pair of laterally disposed jib cranes and said independently traveling bridge crane means includes a pair of independently traveling portal cranes arranged in tandem, each spanning transversely the distance between said auxiliary girders and operatively riding along said auxiliary girders which serve as tracks therefor.

5. Arrangement according to claim 4 wherein said auxiliary girders are in the form of box beam girders and said crossbeams are supported from below by corresponding bridge piers.

6. Method for constructing multi-span bridges across water in successive spans mainly from heavy prefabricated elements, which comprises establishing at least two longitudinally spaced apart transverse crossbeams supported at the height at which the bridge is to be built as well as a pair of transversely spaced apart longitudinal auxiliary girders laterally outwardly resting thereon and spanning

the longitudinal distance therebetween, such that said auxiliary girders are longitudinally displaceable with respect to said crossbeams and have a length greater than the longitudinal distance between said crossbeams to provide corresponding cantilever free ends of said auxiliary girders longitudinally extending substantially beyond said crossbeams, providing independently travelling bridge crane means disposed for longitudinal travel on said auxiliary girders, maintaining an island platform independently removably positioned in the water ahead of the corresponding free ends of said auxiliary girders at a distance corresponding to the next span to be constructed in the forward longitudinal direction of construction of the bridge with island crane means and island support means disposed thereon, drawing said free ends of the auxiliary girders by said island crane means longitudinally forward to said island support means and placing said free ends in resting support thereon while advancing in turn the remainder of said auxiliary girders along said crossbeams, transporting by said travelling bridge crane means corresponding heavy prefabricated pile, pier, crossbeam, main bridge span girder and superstructure elements longitudinally along said auxiliary girders while supported by said island support means, sinking said pile and pier elements at the appropriate bridge span distance to form supports for a corresponding crossbeam element and mounting a crossbeam element on said pile and pier elements with the aid of said island crane means, laying corresponding main bridge span girder and superstructure elements laterally between said auxiliary girders and at substantially the same level thereof with the aid of said travelling bridge crane means, and repeating said drawing, placing, transporting, sinking, mounting and laying steps at least one more time, whereby to construct a multispan bridge across water in successive spans.
